UNITED STATES PATENT OFFICE

2,576,053

FURNACE BAFFLE CONSTRUCTION AND ARRANGEMENT

James E. J. Toner, Bethlehem, Pa., assignor to Bethlehem Foundry and Machine Company, Bethlehem, Pa., a corporation of Pennsylvania

Application July 1, 1949, Serial No. 102,518

18 Claims. (Cl. 110—97)

1

This invention relates to new and useful improvements in furnaces, and more particularly to furnaces of the general type disclosed in U. S. Patent No. 2,264,226 granted November 25, 1941.

In this type of furnace, air is introduced tangentially into a tubular combustion chamber and the fuel is supplied to the chamber in an axial direction. From the beginning, in domestic size furnaces of this type, the limitations in respect of the length of the tubular combustion chambers for household installations were such that the combustion chambers could not be made long enough for complete combustion of the fuel to take place within the tubular chambers. The result of this was that not only was the furnace inefficient in operation but substantial smoke was present causing carbonization not only on the walls of the furnace and stack but also at the fuel nozzle to an extent that the latter became inoperative after short periods of use.

One solution to the difficulties presented appeared to be the necessity for intermixing the fuel and air in the tubular combustion chamber to an extent that would insure complete combustion of the fuel within the chamber. In the aforesaid patent this was sought to be accomplished by inserting in the tubular combustion chamber an annular baffle member which, while preventing too rapid movement of the burning fuel toward the outlet end of the chamber, functioned primarily to cause a sudden or abrupt change in the flow of fluid through the combustion chamber thus creating a turbulent condition at the baffle that produced a satisfactory intermixing of the fuel and air for combustion. Later, additional baffles were installed as required.

The baffles of the aforesaid patent furnished an adequate solution to the problem so long as the domestic fuel oils available consisted mainly of distillate oils. However, since the end of the war the use of catalyst cracked oils in domestic heating fuels has increased until at the present time the major proportion of the oils in domestic fuel oils are produced by catalytic cracking processes. These so-called "cat-crack" oils have been found to have different combustion properties and characteristics than distillate oils with the result that the baffle structure of the aforesaid patent did not provide the degree of fuel-air mixture required to effect complete combustion of such "cat-crack" oils within the relatively short tubular combustion chambers of domestic size furnaces.

With the foregoing in mind, the principal ob-

2

ject of the present invention is to provide for a furnace of the type described a novel baffle construction which is operable to effect an intermixing of fuel and air to a degree causing complete combustion of the fuel to take place within the furnace combustion chamber.

Another object of the invention is to provide a novel baffle construction as set forth which is operable to cause a sudden and abrupt change in the flow of fluid through a tubular combustion chamber and to create a maximum degree of turbulence in the fluid at and through the baffle to thereby cause maximum intermixture of the fuel and air and insure complete combustion of the mixture within the chamber.

A further object of the invention is to provide in a furnace of the type set forth a novel arrangement of baffles embodying the aforesaid features and advantages.

20 These and other objects of the invention and the various features and details of the construction and operation thereof are hereinafter fully set forth and described with reference to the accompanying drawings, in which:

25 Fig. 1 is a longitudinal sectional view vertically through a furnace embodying the present invention;

Fig. 2 is a view in perspective of a baffle member constructed according to the present invention, a portion thereof being broken away to better illustrate certain details of the construction;

Fig. 3 is an enlarged elevational view of the baffle from the outlet end thereof;

Fig. 4 is a sectional view taken on line 4—4, Fig. 3;

30 Fig. 5 is a fragmentary sectional view of the combustion chamber of a furnace showing a baffle arrangement different from that in Fig. 1;

Fig. 6 is a view similar to Fig. 2 of a modified form of baffle;

Fig. 7 is an enlarged elevational view of the baffle construction shown in Fig. 6, from the outlet end thereof;

Fig. 8 is a sectional view on line 8—8, Fig. 7; and

45 Figs. 9 and 10, respectively, are fragmentary sectional views showing other arrangements of baffles which give satisfactory results.

Referring now to the drawing, the invention 50 is shown in conjunction with a domestic furnace of the type described comprising an open-ended tubular combustion chamber 1 and a surrounding series of open-ended fire tubes 2. Air is introduced tangentially into the combustion tube 1 by means of a blower 3 and the fuel to be burned

is discharged coaxially into the chamber 1 by means of a suitable nozzle 4 having associated therewith the customary spark ignition 5.

The combustion gases leaving the outlet end of the tubular combustion chamber 1 make a return pass through the fire tubes 2 and are then discharged up the usual stack 6. The tubular combustion chamber 1 is lined with a plurality of refractory sleeves 7 interspersed with baffles 8 and 9 arranged, for example, as shown in Fig. 1 of the drawing. The baffle 8 may be of the type and construction shown and described in the patent previously referred to herein.

The present invention is concerned primarily with the construction of the baffle 9 and the arrangement of one or more such baffles within the tubular combustion chamber 1 of the furnace. Referring now more particularly to Figs. 2, 3 and 4 of the drawing, the baffle 9 is of a generally annular construction and preferably is fabricated of refractory material. The baffle has a generally tapered opening 10 therethrough which diverges in the direction of passage of the air and fuel therethrough. As shown in the drawing, the opening 10 through the baffle 9 is of irregular configuration or shape and is provided with a plurality of recesses 11 arranged in uniformly spaced relation about the baffle opening 10 and the contour of the recesses 11 is such that there is formed between adjacent recesses a rib portion 12 which projects inwardly of the baffle toward the center of the opening of the baffle, the ribs 12 being disposed alternately with said recesses around the baffle opening 10.

As shown in Fig. 4 of the drawing, the surfaces of the recesses 11 and the surfaces of the ribs 12 both slope outwardly or diverge in the direction of fluid flow through the baffle opening. Furthermore, as will be apparent from a reference to Fig. 3 of the drawing, the arrangement of the recesses 11 and ribs 12 as well as the angle of divergence of their respective surfaces is such that the baffle opening 10 is of correspondingly irregular contour at both the inlet and outlet sides of the baffle.

In a tubular combustion chamber, for example, such as shown in Fig. 1 of the drawing, the inlet end face 13 of the baffle 9 constitutes a barrier which effects a sudden change in the direction of flow of the air through the chamber and sets up a high degree of turbulence in the air resulting in a substantial initial mixture of the air and fuel which, by reason of the pressure of the continuously incoming air supplied to the combustion chamber, is caused to flow in a generally spiral course through the opening 10 in the baffle. As the partially mixed fuel and air thus moves in a spiral course through the opening of the baffle 9, the irregular surface which is provided by the alternately arranged recesses 11 and inwardly projecting or raised rib portions 12, creates a very high degree of turbulence in the fluid as it passes through the baffle thereby causing substantially complete intermixing of the fuel and air and producing a highly combustible mixture which is completely burned during the remainder of its passage through the adjacent refractory sleeve 7, baffle 8 and subsequent sleeves 7 prior to reaching the outlet end of the tubular combustion chamber. Another arrangement of a plurality of baffles 9 in association with sleeves 7 and a baffle 8 in a tubular combustion chamber of longer length is shown in Fig. 5 of the drawing. A modified form of the baffle is shown in Figs. 6, 7 and 8 of the drawing wherein there is

illustrated a baffle member 9a, of generally annular construction, having a generally tapered opening 10a therethrough which diverges in the direction of passage of the air and fuel through the baffle and is provided with a plurality of recesses 11a arranged in uniformly spaced relation about the baffle opening 10a with respect to the alternately arranged ribs 12a that project inwardly of the baffle toward the opening there-through.

As shown in the drawing, the surfaces of the recesses 11a and the surfaces of the ribs 12a both slope outwardly or diverge in the direction of flow through the baffle opening 10a and, in this particular embodiment of the baffle construction, the angle of slope or divergence of the baffle surfaces surrounding the opening 10a is greater than the angle of slope of the corresponding surfaces of the baffle construction previously described so that in the construction of Figs. 6, 7 and 8 the surfaces merge into a truly circular surface surrounding the baffle opening 10a at the outlet side of the baffle. Thus, in the form of baffle construction shown in Figs. 6, 7, and 8, the baffle opening 10a is of irregular contour at the inlet side only of the baffle and is of truly circular contour or shape at the outlet side thereof. The operation of the several recesses 11a and ribs 12a in the baffle construction of Figs. 6, 7 and 8 to create a high degree of turbulence and intermixture of air and fuel during passage thereof through the baffle opening 10a is substantially the same as that set forth with respect to the baffle construction shown in Figs. 2, 3 and 4.

Other arrangements of baffles which give satisfactory results are shown in Figs. 9 and 10 of the drawings, Fig. 9 showing a modified arrangement of the baffle assembly of Fig. 1 and Fig. 10 showing a modification of the baffle assembly of Fig. 5. In the case of Figs. 9 and 10 the baffle arrangements are similar, respectively, to those shown in Figs. 1 and 5 of the drawings except there has been added intermediate the first baffle 9 or 9a and the sleeve 7 or 7a, as the case may be, a baffle 14 or 14a, respectively, having a tapered internal opening of circular configuration with the larger end of said opening facing the inlet end of the combustion tube so that the smaller end of the opening is disposed contiguous to the inlet end of the opening 10 or 10a in the irregularly contoured baffles 9 or 9a, respectively. The use of a baffle 14 or 14a constructed and arranged as described provides with the adjacent baffle of irregular contour a restriction in the combustion chambers which functions in the manner of a nozzle or venturi to provide increased turbulence and more complete intermixing of the air and fuel passing therethrough.

From the foregoing description it will be observed that the present invention provides a novel baffle construction for furnaces of the type described which embodies novel features of construction and arrangement operable to effect a maximum intermixing of fuel and air to the degree required to effect complete combustion of so-called "cat-crack" oils within the tubular combustion chamber of the furnace. The invention also provides a novel baffle construction as set forth which in addition to effecting a sudden or abrupt change in the direction of flow through the combustion chamber operates effectively to create a high degree of turbulence in the fluid as the latter passes through the baffle thereby to effect optimum intermixture of the fuel and air and insure complete combustion thereof within

the limits of the combustion tube of the furnace. While certain embodiments of the present invention have been illustrated and described herein, it is not intended to limit the invention to such disclosures, and changes and modifications may be made therein and thereto within the scope of the following claims.

I claim:

1. As an article of manufacture, a baffle comprising a generally annular member having a tapered internal opening therethrough of irregular configuration defined by alternately disposed recesses and ribs extending axially of the member and arranged in uniformly spaced relation around said opening, said recesses being tapered in the direction of taper of the opening through the member and said ribs being tapered in the opposite direction.

2. As an article of manufacture, a baffle comprising a generally annular member having a tapered internal opening therethrough of irregular configuration defined by alternately disposed recesses and ribs extending axially of the member and arranged in uniformly spaced relation around said opening, the surfaces of said recesses and ribs sloping entirely through the baffle opening at a predetermined angle to cause said opening to be of corresponding irregular contour at both ends thereof.

3. As an article of manufacture, a baffle comprising a generally annular member having a tapered internal opening therethrough of irregular configuration defined by alternately disposed rounded recesses, and inwardly projected ribs extending axially of the member and arranged in uniformly spaced relation around said opening, said recesses being tapered in the direction of taper of the opening through the member and said ribs being tapered in the opposite direction.

4. As an article of manufacture, a baffle comprising a generally annular member having a tapered internal opening therethrough of irregular configuration defined by alternately disposed recesses and ribs extending axially of the member and arranged in uniformly spaced relation around said opening, the surfaces of said recesses and ribs sloping entirely through the baffle opening at a predetermined angle to cause said opening to be of correspondingly irregular contour at both ends thereof, said recesses being tapered in the direction of taper of the opening through the member and said ribs being tapered in the opposite direction.

5. As an article of manufacture, a baffle comprising a generally annular member having a tapered internal opening therethrough of irregular configuration defined by alternately disposed recesses and ribs arranged in uniformly spaced relation around said opening, the surfaces of said recesses and ribs sloping in one direction through the baffle at a predetermined angle to cause said surfaces to merge into a circular surface adjacent one end of the opening and thereby provide a baffle opening of regular contour at said one end, the other end of the baffle opening having an irregular contour.

6. As an article of manufacture, a baffle comprising a generally annular member having a tapered internal opening therethrough of irregular configuration defined by alternately disposed rounded recesses and inwardly projected ribs arranged in uniformly spaced relation around said opening, the surfaces of said recesses and ribs sloping in one direction through the baffle at a predetermined angle to cause said surfaces to

merge into a circular surface adjacent one end of the opening and thereby provide a baffle opening of regular contour at said one end, the other end of the baffle opening having an irregular contour.

7. In a furnace comprising a cylindrical combustion tube to the inlet end of which air is supplied tangentially and fluid fuel is introduced axially thereof, at least one baffle in said tube inwardly adjacent the inlet end of the tube having a tapered internal opening of irregular configuration constituted of alternately arranged recesses and ribs with the smaller end of said opening disposed adjacent said inlet end of the tube, at least one sleeve section lining the tube at the other end of said baffle, and another baffle in the tube at the other side of said sleeve from the first mentioned baffle and having a tapered internal opening of circular configuration with the smaller end thereof disposed adjacent said sleeve.

8. In a furnace comprising a cylindrical combustion tube to the inlet end of which air is supplied tangentially and fluid fuel is introduced axially thereof, at least one baffle in said tube inwardly adjacent the inlet end of the tube having a tapered internal opening of irregular configuration constituted of alternately arranged recesses and ribs with the smaller end of said opening disposed adjacent said inlet end of the tube, the surfaces of said recesses and ribs sloping entirely through the baffle at a predetermined angle to cause the opening to be of correspondingly irregular contour at both ends thereof, a sleeve section lining the tube at the other end of said baffle, and another baffle in the tube at the other side of said sleeve from the first mentioned baffle and having a tapered internal opening of circular configuration with the smaller end thereof disposed adjacent said sleeve.

9. In a furnace comprising a cylindrical combustion tube to the inlet end of which air is supplied tangentially and fluid fuel is introduced axially thereof, at least one baffle in said tube inwardly adjacent the tube inlet end having a tapered internal opening of irregular configuration constituted of alternately arranged recesses and ribs with the smaller end of said opening disposed adjacent the inlet end of the tube, the surfaces of said recesses and ribs sloping through the baffle at a predetermined angle to cause said surfaces to merge into a circular surface adjacent the larger end of the opening and thereby provide a baffle opening of regular contour at said larger end with the smaller end of the baffle opening having an irregular contour, and another baffle in the tube spaced longitudinally thereof from the first baffle and having a tapered internal opening of circular configuration with the smaller end thereof disposed adjacent said first baffle.

10. In a furnace comprising a cylindrical combustion tube to the inlet end of which air is supplied tangentially and fluid fuel is introduced axially thereof, a sleeve section lining the inlet end portion of the combustion tube, a pair of baffles in juxtaposition in said tube inwardly adjacent the sleeve section each having a tapered internal opening of irregular configuration constituted of alternately arranged recesses and ribs with the smaller end of the opening disposed adjacent the inlet end of the tube, a plurality of sleeve sections lining the tube at the other end of said pair of baffles, another baffle

in the tube adjacent said plurality of sleeves having a tapered internal opening of circular configuration with the smaller end thereof facing the inlet end of the tube, and a plurality of additional sleeve sections lining said tube at the other end of said other baffle.

11. In a furnace comprising a cylindrical combustion tube to the inlet end of which air is supplied tangentially and fluid fuel is introduced axially thereof, a pair of baffles in said tube inwardly adjacent the inlet end thereof each having a tapered internal opening of irregular configuration constituted of alternately arranged recesses and ribs with the smaller end of the opening disposed adjacent the inlet end of the tube, the surfaces of said recesses and ribs sloping entirely through the baffle at a predetermined angle to cause the opening to be of correspondingly irregular contour at both ends thereof, a plurality of sleeve sections lining the tube at the other end of said pair of baffles, and another baffle in the tube adjacent said sleeves and having a tapered internal opening of circular configuration with the smaller end thereof facing said pair of baffles.

12. In a furnace comprising a cylindrical combustion tube to the inlet end of which air is supplied tangentially and fluid fuel is introduced axially thereof, a sleeve section lining the inlet end portion of the combustion tube, a pair of baffles in said tube inwardly adjacent the sleeve section each having a tapered internal opening of irregular configuration constituted of alternately arranged recesses and ribs with the smaller end of the opening disposed adjacent the inlet end of the tube, the surfaces of said recesses and ribs sloping through the baffle at a predetermined angle to cause said surfaces to merge into a circular surface adjacent the larger end of the opening and thereby provide a baffle opening of regular contour at said larger end with the smaller end of the baffle opening having an irregular contour, a plurality of sleeve sections lining the tube at the other end of said pair of baffles, another baffle in the tube adjacent the last-mentioned sleeves having a tapered internal opening of circular configuration with the smaller end thereof facing the inlet end of the tube, and a plurality of additional sleeve sections lining said tube at the other end of said other baffle.

13. In a furnace comprising a cylindrical combustion tube to the inlet end of which air is supplied tangentially and fluid fuel is introduced axially thereof, a sleeve section lining the inlet end portion of the combustion tube, a first baffle in the tube adjacent the sleeve and having a tapered internal opening of circular configuration with the larger end thereof adjacent said sleeve, and a second baffle in said tube inwardly adjacent the first baffle and having a tapered internal opening of irregular configuration constituted of alternately arranged recesses and ribs with the smaller end of said opening disposed adjacent said first baffle.

14. In a furnace comprising a cylindrical combustion tube to the inlet end of which air is supplied tangentially and fluid fuel is introduced axially thereof, a sleeve section lining the inlet end portion of the combustion tube, a first baffle in the tube adjacent the sleeve and having a tapered internal opening of circular configuration with the larger end thereof adjacent said sleeve, a second baffle in said tube inwardly adjacent the first baffle and having a tapered in-

ternal opening of irregular configuration constituted of alternately arranged recesses and ribs with the smaller end of said opening disposed adjacent said first baffle, the surfaces of said recesses and ribs sloping through the baffle at a predetermined angle to cause the opening to be of correspondingly irregular contour at both ends thereof.

15. In a furnace comprising a cylindrical combustion tube to the inlet end of which air is supplied tangentially and fluid fuel is introduced axially thereof, a sleeve section lining the inlet end portion of the combustion tube, a first baffle in the tube adjacent the sleeve and having a tapered internal opening of circular configuration with the larger end thereof adjacent said sleeve, a second baffle in said tube inwardly adjacent the first baffle and having a tapered internal opening of irregular configuration constituted of alternately arranged recesses and ribs with the smaller end of said opening disposed adjacent said first baffle, a sleeve lining the tube at the other end of said second baffle, and another baffle in the tube adjacent the last-mentioned sleeve having a tapered internal opening of circular configuration with the smaller end thereof disposed adjacent said sleeve.

16. In a furnace comprising a cylindrical combustion tube to the inlet end of which air is supplied tangentially and fluid fuel is introduced axially thereof, a sleeve section lining the inlet end portion of the combustion tube, a first baffle in the tube adjacent the sleeve and having a tapered internal opening of circular configuration with the larger end thereof adjacent said sleeve, and a pair of baffles in said tube inwardly adjacent the first baffle each having a tapered internal opening of irregular configuration constituted of alternately arranged recesses and ribs with the smaller end of said opening disposed adjacent said first baffle.

17. In a furnace comprising a cylindrical combustion tube to the inlet end of which air is supplied tangentially and fluid fuel is introduced axially thereof, a sleeve section lining the inlet end portion of the combustion tube, a first baffle in the tube adjacent the sleeve and having a tapered internal opening of circular configuration with the larger end thereof adjacent said sleeve, and a pair of baffles in said tube inwardly adjacent the first baffle each having a tapered internal opening of irregular configuration constituted of alternately arranged recesses and ribs with the smaller end of said opening disposed adjacent first baffle, the surfaces of said recesses and ribs sloping through the baffle at a predetermined angle to cause the opening to be of correspondingly irregular contour at both ends thereof.

18. In a furnace comprising a cylindrical combustion tube to the inlet end of which air is supplied tangentially and fluid fuel is introduced axially thereof, a sleeve section lining the inlet end portion of the combustion tube, a first baffle in the tube adjacent the sleeve and having a tapered internal opening of circular configuration with the larger end thereof adjacent said sleeve, and a pair of baffles in said tube inwardly adjacent the first baffle each having a tapered internal opening of irregular configuration constituted of alternately arranged recesses and ribs with the smaller end of said opening disposed adjacent said first baffle, the surfaces of said recesses and ribs sloping through the baffle at a predetermined angle to cause the opening to be

9

of correspondingly irregular contour at both ends thereof, sleeve sections lining the tube at the other end of said pair of baffles, and another baffle in the tube adjacent the last-mentioned sleeves and having a tapered internal opening of circular configuration with the smaller end thereof disposed adjacent said sleeves.
